MICHAEL JOHN WILLCOCKS

By D. J. M. Whan Attorney

UNITED STATES PATENT OFFICE.

MICHAEL JOHN WILLCOCKS, OF CLEVEDON, ENGLAND.

SPARKING PLUG.

1,325,549.

Specification of Letters Patent. Patented Dec. 23, 1919.

Application filed September 28, 1918. Serial No. 256,014.

To all whom it may concern:

Be it known that I, MICHAEL JOHN WILLCOCKS, a subject of the King of Great Britain and Ireland, and a resident of Clevedon, 5 county of Somerset, England, have invented a certain new and useful Improvement in or Relating to Sparking Plugs, of which the following is a specification.

This invention of improvements in or 10 relating to sparking plugs has for its object the provision of an improved means whereby said sparking plugs are effectively air-cooled, and the invention is characterized, in one form, by an annular chamber 15 which is absolutely gas or fluid-tight in relation to the combustion chamber or cylinder, located within the plug and at the sparking end thereof, said chamber being formed by the outer wall of the plug, the 20 shoulder thereon and sparking end thereof, and an unperforated and externally gilled sleeve which makes a gas or fluid-tight joint with said shoulder and sparking end, said chamber, which incloses the insulating 25 interior, being provided with inlet and outlet passages located between any point where the insulating interior or its washer makes contact with the body of the plug or sleeve and the surface of the cylinder.

30 The accompanying sheets of drawing illustrate various ways of accomplishing the invention.

Of the drawings:

Figure 1 is a view partly in section and 35 partly in elevation of a plug constructed in accordance with the invention.

Fig. 2 is a sectional view of the body of the plug detached.

Fig. 3 is an elevation of the sleeve employed.

Fig. 4 is a sectional plan view taken on line 1—1 of Fig. 1.

Fig. 5 is a fragmentary sectional view showing a modified arrangement of sleeve.

Fig. 6 is a sectional view taken on line 2—2 of Fig. 5.

Fig. 7 is a fragmentary sectional view showing the cooling chamber formed in the metal of the plug.

50 Fig. 8 is a sectional plan view taken on line 3—3 of said Fig. 7.

Fig. 9 is a fragmentary sectional plan view showing another manner of forming the cooling chamber in the metal of the plug.

55

Fig. 10 is a sectional plan view taken on line 4—4 of said Fig. 9.

Fig. 11 is a fragmentary sectional view showing a still further manner of forming the cooling chamber.

60

Fig. 12 is a sectional plan view taken on line 5—5 of said Fig. 11.

Like letters of reference indicate corresponding parts in the several figures.

In carrying out the invention, and referring first to Figs. 1 to 4, the annular chamber *a* is formed in the metal portion *b* of the plug which screws into the engine cylinder by turning away a portion of the outer wall *b'* to the required depth and then 70 inserting a sleeve *c* provided with a flange *c'* which rests on the shoulder *b* against which the insulating interior *d* would ordinarily be butted, so that when said insulating interior *d* is in place and the nut *d'* which secures it is screwed home, said sleeve 75 *c* is gripped by its flange *c'* between the shoulder *b* and the washer *d* placed between said insulating interior *d* and said shoulder *b*.

80

Through the chamber *a* which extends from near the shoulder *b* almost to the sparking end of the plug passes the sleeve *c*, which sleeve *c* in its length is stepped or made internally and externally of two different diameters, the larger being provided with the flange *c'*, and the smaller at its lower end with an externally screw-threaded shoulder *c* which screws into a tapped hole *b* in the lower end of the plug and protrudes therefrom, said protruding portion being afterward spun outward and over the end *b* of the plug, thus making a most efficient joint or closure to the chamber *a*.

85

At the upper end of the chamber *a* lateral passages *a'*, *a* are provided, which passages *a'*, *a* put the interior of said chamber *a* into communication with the external atmosphere, the passage *a'* being connected to a funnel *e*, the mouth *e* of which is made to 90 face the direction in which the engine carrying the sparking plug moves, so that air

95

100

- forced into the chamber a through passage a' will escape by the passage a^2 opposite. Further, to insure the air circulating through the chamber a , there is provided at 5 the top part thereof, and on each side of the air inlet or lateral passage a' , a baffle plate a^3 against which the incoming air impinges and is deflected downward before issuing from the lateral passage a^2 , said baffle plate a^3 being preferably constituted by angle-shaped plates located on the inner wall joining the air passages a' , a^2 , and secured to said wall and the flanges of the funnel e by rivets or other suitable means, and to 10 insure a more efficient cooling of the sleeve c , the same is, at its reduced portion c^3 , provided with a series of superimposed external gills c^4 taking in the lower part of the annular chamber a . 15 20 If desired, two or more air inlets or lateral passages may be employed and connected up with the beforementioned funnel, or be connected up with a fan or blower.

Referring now to the arrangement shown 25 in Figs. 5 and 6, the sleeve c instead of being made stepped or of two diameters and provided with an externally threaded shoulder and with gills, is now made plain and of one diameter and its end portion c^5 passed 30 through an untapped hole b^8 in the end b^4 of the plug and welded thereto and then spun over an inwardly directed lip on said end b^4 to hold in position a point carrying ring f . 35 Or, instead of using a separate and interior sleeve as previously described, the plug portion b may, as shown in Figs. 7 and 8, be machined from upper part to provide an annular chamber a within it, a thin cylindrical wall c^6 being left between the machined part and the portion within which the insulating interior, not shown, fits, and the end c^7 of the wall c^6 spun over on to the shoulder b^2 as shown in full lines to close 40 45 the chamber a , or, as shown in dotted lines, and, further, may be welded to the opposite wall.

Or, the plug may be machined from its 50 sparking end, as shown in Figs. 9 and 10, and the end c^7 of the cylindrical wall c^6 be spun over the end b^4 of the plug and be welded thereto.

Or, instead of employing an annular chamber in the plug, the same may be replaced, as shown in Figs. 11 and 12, by a 55 number of longitudinal passages a^4 drilled in the body portion of the plug, the ends of the passages which are toward the engine being closed by plugs a^5 , and a corresponding number of lateral passages a^6 60 drilled from the exterior to meet the longitudinal passages a^4 , so that the external atmosphere is admitted to said longitudinal passages a^4 , the circulation in these passages 65 being by convection.

In the various modifications shown by Figs. 5 to 10 the air inlets may, as in the first described and shown arrangement, be connected to an inlet funnel.

Having now described my invention, what 70 I claim as new and desire to secure by Letters Patent of the United States is:—

1. In air-cooled sparking plugs, an annular chamber which is absolutely gas or fluid-tight in relation to the combustion chamber or cylinder, located within the plug and at the sparking end thereof, said chamber being formed by the outer wall of the plug, the shoulder thereon and sparking end thereof, and an unperforated and externally 75 gilled sleeve which makes a gas or fluid-tight joint with said shoulder and sparking end, said chamber, which incloses the insulating interior, being provided with inlet and outlet passages located between any 80 point where the insulating interior or its washer makes contact with the body of the plug or sleeve and the surface of the cylinder.

2. An air-cooled spark plug, including a 90 plug body having its sparking end formed hollow, and provided with ports open to the atmosphere and also an interior shoulder above the ports, and a sleeve arranged within the hollow portion of the plug body to 95 provide an annular chamber, said sleeve being of two different diameters, the larger of which is provided with an outwardly extending flange, while the smaller is provided with a series of external gills and at its 100 lower end with an externally screw threaded portion adapted to screw into the sparking end of the plug body while said flange abuts against the shoulder above the ports, whereby when said sleeve is screwed into the 105 sparking end and spun thereover and the flange of the sleeve is pressed onto the shoulder of the plug by the insulating interior and its nut, an efficient joint is provided for the annular chamber.

3. An air-cooled spark plug having its 110 sparking end formed hollow and provided with ports open to the atmosphere, a sleeve fitted in the sparking end of the plug body to provide an annular interior chamber, and baffle plates arranged in the upper part of the annular chamber and between the said ports, whereby air entering one of the same will be deflected down into the bottom of the chamber.

4. A spark plug including a plug body having its sparking end formed with a chamber of relatively large diameter and provided with inlet and outlet ports, a sleeve adapted to be fitted within the chamber and provided at its upper end with a flange whereby when its lower end is fitted to the bottom portion of the plug body the said flange may be drawn tightly against an abutting part of the plug body above the 115 120 125 130

ports to provide a tight joint, while the said lower end may be united with the bottom of the plug body to provide a tight joint at this point also.

5 5. A spark plug including a hollow body having an intake port, and a tubular member of less diameter than said body and ar-

ranged therein to form an annular air chamber in communication with said port and located at the sparking end of the plug. 10

In testimony whereof I have affixed my signature hereto this 2nd day of September, 1918.

MICHAEL JOHN WILLCOCKS.
